UNITED STATES PATENT OFFICE.

EDWARD L. DILLMAN, OF NEW YORK, N. Y.

MEDICATED PEG.

Application filed June 26, 1928. Serial No. 288,460.

My invention relates to medicated pegs, and I use this term because the device is in the nature of a peg which can be grasped by the fingers or by a proper instrument and forced 5 to move with a certain degree of pressure into a tooth cavity or other opening and broken off at the desired place.

An object of the invention is to provide a medicated peg or point which is dry, reasonably hard but brittle, which is readily soluble, and is adapted to relieve pain, to heal wounds 10 or perform any analogous function as a medicated sanitary device.

The specific use of my invention is to relieve toothache and the peg can be easily forced into the cavity of the tooth, or in the opening of the gum after a tooth is withdrawn, and broken off so as to leave the proper 15 length of peg in the cavity or opening, and the peg will dissolve and adhere to the surfaces so that its antiseptic and medicated qualities may have free and full application 20 to the nerves and tissues so as to relieve pain and heal a wound.

I of course do not wish to be limited to the particular use to which my improved medicated peg may be put as it has a wide range 25 of usefulness and its ingredients may be varied so as to adapt the peg for any use.

I am of course aware that suppositories and other more or less soft and sticky medicated devices have been employed but my improved peg is dry, reasonably hard but brittle, and can be handled easily and most effectually forced into a cavity or other wound 30 and broken off at the length desired, which makes it altogether a different article from suppositories, pellets and other forms of article now in use.

Further objects will hereinafter appear in connection with the following description.

In the accompanying drawings—

Figure 1 illustrates the operation of placing one of my improved pegs in the cavity of a tooth;

Figure 2 is a perspective view greatly enlarged of one of my improved pegs.

Referring to the drawings, Figure 1 rep-

resents my improved peg, which is shown as of somewhat wedge-shape, tapering to a point 50 2, and this point may be as blunt or as sharp as desired, and the peg may of course be otherwise shaped without departing from my invention.

In Figure 1 I illustrate the peg 1 grasped 55 between the thumb and finger of a hand 3 and in the operation of being forced into a cavity 4 of a tooth 5. When the peg is forced into the cavity it is broken off at the surface of the tooth by a lateral movement of the hand, leaving a length of peg in the cavity; and this portion in the cavity of the tooth is dissolved by the saliva of the mouth and completely fills the cavity and exposed nerve 60 65 passages so as to stop the pain.

In making my improved pegs I may employ a wide range of materials but, in any event, the material will be dry and pegs cut or otherwise formed therefrom, so that the finished peg will be dry, relatively hard but 70 brittle.

As an example of a composition that may be employed in making the peg, I compound novocain, novethene, mercurochrome, pyridium, eugenol, thymol, in synergistic combination, activated by a catalytic agent which 75 produces prolonged anesthesia.

It is of course not necessary for me to enumerate the many uses to which a peg of this character may be put as I desire to cover 80 broadly the idea of a peg or a device of this character under any other name.

I claim:

As a new article of manufacture, a pointed medicated brittle absorbent peg of a length 85 adapted to be grasped between the thumb and finger of a hand and forced into the cavity of a tooth or wound, and broken off or crushed, whereby the cavity is approximately filled, said portion in the cavity adapted to be dissolved by the saliva of the mouth or the moisture of the wound.

Signed at New York in the county of New York and State of New York this 25th day of June, A. D. 1928.

EDWARD L. DILLMAN.
